J. F. DELANEY

PIPE WRENCH

Filed Feb. 7, 1923

INVENTOR:

John F. Delaney
By his attorney
Charles S. Goodwin

UNITED STATES PATENT OFFICE.

JOHN F. DELANEY, OF BOSTON, MASSACHUSETTS.

PIPE WRENCH.

Application filed February 7, 1923. Serial No. 617,477.

To all whom it may concern:

Be it known that I, JOHN F. DELANEY, a citizen of the United States, residing at Boston, in the county of Suffolk and State of Massachusetts, have invented new and useful Improvements in Pipe Wrenches, of which the following is a specification.

This invention relates to an improved wrench particularly adapted for use in connection with cylindrical objects such as pipes, rods and the like, and is of the general type well known as the Stillson wrench.

The object of the invention is to provide a wrench of the character set forth which, while being strong and possessing all the mechanical advantages of a Stillson wrench, is cheaper to manufacture. To this end the yoke which connects the auxiliary jaw shank to the main jaw shank is made in two parts. Preferably, and as hereinafter set forth, the two parts of the yoke are made duplicates of each other and are attached to the main shank by a single pin, bolt or stud, but are reversely disposed upon opposite sides respectively of the main shank and their free ends engage opposite faces of the auxiliary shank at opposite ends of the nut whereby the auxiliary shank is moved relatively to the main shank of the wrench to increase or diminish the space between the jaws.

The invention consists particularly in the two part yoke whereby the auxiliary jaw is positioned upon the main jaw.

To these ends the invention consists in the combination and arrangement of parts set forth in the following specification and particularly pointed out in the claims thereof.

Referring to the drawings:

Figure 1 is a front elevation of my improved wrench.

Fig. 2 is a side elevation of the same as viewed from the left of Fig. 1, the handle being broken away.

Fig. 3 is a sectional elevation taken on the line 3—3 of Fig. 1, and viewed from the right of Fig. 1.

Fig. 4 is a front elevation of one of the yoke arms,

Fig. 5 is an underneath plan of the same, and

Fig. 6 is a side elevation viewed from the right of Fig. 4.

Like numerals refer to like parts throughout the several views of the drawings.

In the drawings, 10 is the main shank,

the end being provided with the usual jaw 11 and having a handle 12 forming a part thereof. 13 is an auxiliary shank terminating in another jaw 14. The auxiliary shank 13 is screw-threaded at 15 and has screw-threaded engagement with a nut 16. All of these parts are substantially the same as the Stillson wrench of commerce. The yoke consists of two arms 17 and 18 duplicates of each other which are connected to the main shank 10 by a pin 19. The arms 17 and 18 are reversely disposed so that the free end of the arm 17 engages the upper edge of the nut 16 while the free end of the arm 18 engages the lower edge of said nut. Each of the arms 17 and 18 terminates at its outer end in a semi-cylindrical portion 20, and each of said arms has a flat inner face 21. A segmental sleeve 22 is provided upon each of said arms which extends downwardly from the portion 20 of the arm 17 and upwardly from the portion 20 of the arm 18, projecting through the nut 16, and engaging opposite faces thereof. Each of the segmental flanges 22 terminates in a flange 23 and when in operative position the flange 23 of the arm 17 engages the under side of the nut 16 and the flange 23 of the arm 18 engages the upper edge of said nut. A spring 24 is fastened at one end to the main shank 10 and its free end bears against the inner edge of the auxiliary shank 13. The parts are assembled by slipping the segmental flanges 22 of the arms 17 and 18 through the nut 16 in opposite directions respectively. The said arms are then fastened to opposite faces of the main shank 10 by means of a pin 19 which is secured thereto by riveting. The auxiliary shank is then inserted in the nut between the flat adjacent faces 21 of the arms 17 and 18 until the lower end thereof is engaged by the nut 16, whereupon by rotating the nut in the proper direction, the auxiliary flange and its jaw will be brought downwardly adjacent to the main shank 10 until the parts assume the relative positions illustrated in Figure 1.

It will be seen that the two arms 17 and 18, duplicates of each other, and of the construction hereinbefore described and illustrated in the drawings, are very much cheaper to manufacture than the yoke of the Stillson wrench of commerce, which being made of one piece has to be made of malleable iron, or of some casting and cored

and machined taking several processes to produce the same, and constituting a very expensive article. By making the arms separate, they can be made of forged steel, 5 that is, of the same material as the jaws of the wrench and can be hardened and tempered.

If desired, these arms could of course be moulded in large quantities without the 10 use, however, of any cores and with less difficulty, labor and expense. The only machine work, of course, necessary in the arms of the present invention is that upon the flat face 21 and the drilling of the pin hole.

15 It will be seen that the two arms, when assembled with the main and the auxiliary shanks hold the nut in place and prevent the same from slipping up or down. In other words, it fulfills all the functions performed by the yoke of the Stillson wrench 20 of commerce and can be produced in much larger quantities and less time, hence can be manufactured at a much smaller cost.

While the construction hereinbefore set 25 forth and the drawings illustrate the two arms 17 and 18 as being secured to the main shank 10 by a single pin 19, it is evident that these jaws may be secured to the shank 10 in any suitable manner, such as by two 30 rivets instead of one, without departing from the spirit of my invention.

I claim:

1. A wrench having, in combination, a main shank with a jaw thereon, an auxiliary shank with a jaw thereon, a nut having 35 screw-threaded engagement with said auxiliary jaw, a yoke comprising two independent separable arms and means securing said arms to the main shank, the free ends of 40 each of said arms engaging opposite ends of said nut.

2. A wrench having, in combination, a main shank with a jaw thereon, an auxiliary shank with a jaw thereon, a nut having 45 screw-threaded engagement with said auxiliary jaw, a yoke comprising two independent arms and means securing said arms to the main shank, the free ends of said arms 50 engaging opposite ends of said nut and opposite faces respectively of said auxiliary shank.

3. A wrench having, in combination, a main shank with a jaw thereon, an auxiliary shank with a jaw thereon, a nut having 55 screw-threaded engagement with said auxiliary jaw, a yoke comprising two independ-

ent arms, means securing said arms to the main shank and a segmental sleeve on the free end of each of said arms projecting through said nut and engaging opposite faces respectively of said auxiliary shank.

4. A wrench having, in combination, a main shank with a jaw thereon, an auxiliary shank with a jaw thereon, a nut having 65 screw-threaded engagement with said auxiliary jaw, a yoke comprising two independent arms, means securing said arms to the main shank, a segmental sleeve on the free end of each of said arms projecting through said nut and engaging opposite faces 70 respectively of said auxiliary shank and a flange on each of said segmental sleeves engaging opposite ends respectively of said nut.

5. A wrench having, in combination, a 75 main shank with a jaw thereon, an auxiliary shank with a jaw thereon, a nut having screw-threaded engagement with said auxiliary jaw, a yoke comprising two independent 80 arms, means securing said arms in reversely disposed positions to said main shank, the free ends of said arms engaging opposite ends of said nut.

6. A wrench having, in combination, a main shank with a jaw thereon, an auxiliary shank with a jaw thereon, a nut having 85 screw-threaded engagement with said auxiliary shank, a yoke comprising two independent arms approximately duplicates of each other and means securing said arms to the main shank in reversely disposed positions, the free ends of said arms engaging 90 opposite ends of said nut.

7. A wrench having, in combination, a main shank with a jaw thereon, an auxiliary shank with a jaw thereon, a nut having 95 screw-threaded engagement with said auxiliary shank, a yoke comprising two independent arms approximately duplicates of each other and means securing said arms to 100 the main shank in reversely disposed positions, the free ends of said arms engaging opposite ends of said nut and opposite faces respectively of said auxiliary shank.

In testimony whereof I have hereunto set 105 my hand in presence of two subscribing witnesses.

JOHN F. DELANEY.
